UNITED STATES PATENT OFFICE.

ALBERT W. SAELESSER, OF GRANITE CITY, ILLINOIS.

DESIGN FOR AN AUTOMOBILE-WHEEL LOCK.

57,729.

Specification for Design.

Patented Apr. 26, 1921.

Application filed September 17, 1920. Serial No. 410,994. Term of patent 14 years.

To all whom it may concern:

Be it known that I, ALBERT W. SAELESSER, a citizen of the United States, residing at Granite City, in the county of Madison and State of Illinois, have invented a new, original, and ornamental Design for Automobile-Wheel Locks, of which the following is a specification, reference being had to the accompanying drawing, forming part thereof.

The figure is a perspective view of an automobile wheel lock showing my new design.

I claim:

The ornamental design for an automobile wheel lock as shown.

ALBERT W. SAELESSER.
